(57) **CLAIM**

The ornamental design for a stand for large stringed instrument, as shown.

DESCRIPTION

FIG. 1 is a front elevation view of a stand for large stringed instrument showing my new design;

FIG. 2 is a bottom plan view thereof;

FIG. 3 is a top plan view thereof;

FIG. 4 is a right side elevation view thereof;

FIG. 5 is a rear elevation view thereof; and,

FIG. 6 is a front, top, left side perspective view thereof.

The cello and bow shown in broken lines in FIG. 6 are shown for illustrative purposes only and form no part of the claimed design.
